UNITED STATES PATENT OFFICE

CHARLES MARCUS, OF NEW YORK, N. Y., ASSIGNOR TO ECLIPSE MACHINE COMPANY,
OF ELMIRA, NEW YORK, A CORPORATION OF NEW YORK

ENGINE STARTER

Application filed May 18, 1925. Serial No. 30,916.

My invention relates to starting apparatus for the starting of internal combustion engines, and the same in the present case is more particularly designed for use in connection 5 with the engines of airplanes. My present invention concerns the construction and mode of operation of the drive or transmission which is located between the engine and the source of power whether it be a manual 10 device or a prime mover, such as an electric motor. The object of my invention is to provide a novel, efficient and improved construction of drive whose features of advantage and utility will be apparent from 15 the description hereinafter given.

In the drawings, Figure 1 is a sectional elevation of a starting apparatus embodying my new construction of drive or transmission, such section being taken on the irregular line 20 1-1 of Fig. 4; Fig. 2 a detail section illustrating the condition of the apparatus when the manually operated device is removed; Fig. 3 an elevation of the apparatus viewed from the pinion or engine engaging end of 25 the apparatus, that is the left hand of Fig. 1; and Fig. 4 an elevation from the opposite side or end of the apparatus.

In the present instance, I have shown a complete engine starting apparatus, and in 30 addition, have shown two sources of power to-wit, an electric motor and a manually operated device, either one or both of which sources of power may be used in the same apparatus, but it will be understood that my 35 present invention is concerned only with the structure and operation of the mechanism constituting the drive or transmission between such sources of power and the member of the engine to be started, the manually operated device in combination with the drive 40 being made the subject matter of a co-pending application for patent.

Describing the engine starting apparatus in its completeness as herein illustrated, the 45 drive or transmission is substantially contained and supported by a main casing 1 and a supplementary casing 2 secured thereto in a suitable manner as by means of screws 3. These casings support the electric motor 4 50 which is vertically disposed so that its arma-

ture shaft is vertical and provided at its lower end with a driving pinion 5. The supplementary casing 2 forms the support or place of attachment of the manually operated device 6 whose operating shaft 7 is provided with a bevel gear 8 meshing with a bevel gear 9 which is operatively connected with the planetary gearing hereinafter described.

The drive or transmission which constitutes the subject matter of the present invention is contained substantially wholly within the main casing 1 and comprises mechanism for transmitting the torque from the source of power and for automatically making the connection between such drive and an engine member when the source of power is operated or energized. By preference, this main casing is provided with an internal bushing 10 within which is arranged to rotate a barrel 11. Concentric with this barrel and separated by a considerable annular space is a rotatable shell 12 which is operatively connected with the barrel so as to be driven thereby with a yieldable pressure. In the present instance, such yielding driving connection is a friction clutch comprising two sets of friction plates 13 and 14, the former of which are splined to the interior of the barrel and the latter of which are splined to the exterior of the shell. These friction plates are located in an annular space on the right hand side of an interior annular rib 15 or abutment of the barrel and between the shoulder 16 on the inner end of the shell and the bushing 17 which is in contact with the abutment 15. On the other or left hand side of this abutment, there is located adjustable spring pressure means for adjusting the tension or pressure upon said friction plates.

The necessary spring pressure is furnished to the multiple plate clutch by means of a nest of small helical springs 18 which in practice are six in number. These springs bear at one end against a spring cage 19 which in turn bears against an adjusting nut 20 and at the other end against a ring abutment 21, such cage being preferably provided with protruding pins 22 which enter the coils for the pur-

pose of supporting them. The abutment 21 clamps between it and the abutment or rib 15 a disk 23 which forms an anti-friction bearing surface between the abutment 21 and the rib or abutment 15. The spring pressure is transmitted through the cage 19 and the nut 20 to the shell 12 to whose outer end such nut is adjustably secured, whereby the clutch plates are clamped between the bushing 17 and the shoulder 16 through the washer 24. An adjustment for the desired spring pressure on the clutch plates is obtained by turning in the proper direction the adjusting nut 20 which is threaded to the exterior of the shell 12. It will be understood that the disk 23 is splined to the shell 12 in the same manner as the clutch plates 13.

Within the shell 12, there is axially or concentrically arranged a screw shaft 25 provided with long lead threads 26 which engage the internally threaded nut portion 27 of the shell 12 whereby rotation of such shell results in the forward longitudinal movement of the shaft 25. This shaft is provided at its outer end with a driving member which is here in the form of a splined portion adapted to engage a member of the engine to be started, such as the internally splined end 29 of the crank shaft of the engine. By preference, a yielding device is provided to act upon the front end of the shaft to assure its longitudinal travel for engagement with the engine member. As shown, this device consists of an internally splined friction plate 30 meshing with the splined end of the shaft and clamped between a dished spring washer 31 and the front wall 32 of a cap 33 which encloses the outer or front end of the drive mechanism, such cap being secured to the main casing in suitable manner as by means of screws 34. The screw shaft 25 is provided at its inner or right hand end with two nuts 35 and 36 which are preferably screwed thereupon and constitute the inner abutment of such shaft by reason of the contact thereof against the bushing 37 constituting the inner or end stop for the shaft.

Describing the planetary gearing, a bevel gear 38 which meshes with and is driven by the bevel gear 5 of the electric motor is secured to a shaft 39 which is in line with the screw shaft 25. The right hand end of this shaft 39 is journaled in the casing 2 and the left hand in the extended hub of the internal gear wheel 40 to which said bushing 37 is secured on its left hand side.

The bevel gear 38 forms a spider for carrying a set of preferably three planetary gear units, each of which comprises a hub 41 having a gear 42 cut thereon at one end and a gear 43 at the other end, the number of teeth of the gear 42 being less than that of the gear 43. Three equidistant openings are preferably provided in the web of the gear 38, through each of which extends one of such planetary

units, each being mounted in place by means of a bolt 44 passing transversely through the spider plates 45 and 46 and secured thereto and having mounted thereon a roller bearing 47 about which the gear hub 41 may rotate. These spider plates 45 and 46 are spaced apart by means of the bolts 48 and the spacer collars 49.

Cooperating with the set of gears 43 is a stationary internal gear 50 which is secured to the casing 2 in a suitable manner as by means of dowels 51 and screws 52. The rotatable internal gear 40 preferably having a somewhat lesser number of teeth than the gear 50 meshes with the set of gears 42 and the web thereof is secured to the rotatable barrel 11 at the point 53.

With respect to the manually operated device for hand cranking the engine, it will be sufficient to state for the purposes of the present invention that a suitable hand crank is applied to the protruding end of the shaft 7 and such shaft is thereby rotated with the result that the bevel gears 8 and 9 and consequently the shaft 39 are rotated. This motion is transmitted through the planetary gearing to the drive and the drive is thereby operated and the engine is cranked.

Describing the operation of the drive and assuming operation by either the electric motor or by the manually operated device, when either source of power is operated, the barrel 11 is rotated. This rotation is transmitted through the friction clutch to the shell 12, and inasmuch as the latter is threaded to the screw shaft, such shaft is advanced or moved longitudinally to the left (Fig. 1) and the splined portion 28 is thereby brought into driving engagement with the engine member 29. When such splined portion is in proper mesh with the engine member, the abutment 35 will bear against and be stopped by the annular shoulder 54 on the interior of the shell whereupon such screw shaft will partake of the rotary movement of the barrel and shell and the engine will thereupon be cranked. When the engine starts on its own power, the excess speed of rotation of the engine member will cause the screw shaft to be screwed backwardly to normal position within its shell 12 and the splined portion 28 to be demeshed, ready for the next operation.

I claim:

1. An engine starter drive including a rotatable barrel, a substantially cylindrical shell concentric of the barrel, a friction clutch operatively connecting the barrel and shell, a rotatable longitudinally movable shaft mounted within and axially of the barrel and shell and carrying at one end a driving member adapted to engage and drive a member of the engine to be started, means coacting with the shell and shaft for actuating the shaft in its longitudinal movements, and means for rotating the barrel.

tatable barrel, a substantially cylindrical shell concentric of the barrel, a friction clutch comprising sets of friction plates splined to the barrel and shell respectively, a rotatable longitudinally movable shaft mounted axially of the barrel and shell and carrying at one end a driving member adapted to engage and drive a member of the engine to be started, means coacting with the shell and shaft for actuating the shaft in its longitudinal movements, means for rotating the barrel, said barrel being provided with an interior annular rib on one side of which the clutch is located, and clutch tightening means located on the other side thereof and contained within the barrel.

10. An engine starter drive including a rotatable barrel having an internal rib, a substantially cylindrical shell concentric of the barrel and having an external shoulder at one end, a friction clutch operatively connecting the barrel and shell and clamped between the rib and shoulder, a rotatable longitudinally movable shaft mounted axially of the barrel and shell and carrying at one end a driving member adapted to engage and drive a member of the engine to be started, means coacting with the shell and shaft for actuating the shaft in its longitudinal movements, means for rotating the barrel, and adjustable tightening means acting on such clutch.

11. An engine starter drive including a rotatable barrel having an internal rib, a substantially cylindrical shell concentric of the barrel and having an external shoulder at its inner end, a friction clutch operatively connecting the barrel and shell and clamped between the rib and shoulder, a rotatable longitudinally movable shaft mounted axially of the barrel and shell and carrying at one end a driving member adapted to engage and drive a member of the engine to be started, means coacting with the shell and shaft for actuating the shaft in its longitudinal movements, means for rotating the barrel, and adjustable tightening means acting on such clutch comprising an adjustable nut on the outer end of the shell and a series of coiled springs interposed between such nut and rib.

12. An engine starter drive including a rotatable barrel, a substantially cylindrical shell concentric of the barrel, a friction clutch operatively connecting the barrel and shell, a rotatable longitudinally movable shaft mounted axially of the barrel and shell and centrally thereof and carrying at one end a driving member which is fixed thereto and adapted to engage and drive a member of the engine to be started, means co-acting with the shell and shaft for actuating the shaft in its longitudinal movements, and means for rotating the barrel.

13. An engine starter drive including a rotatable barrel, a substantially cylindrical

shell concentric of the barrel, a friction clutch operatively connecting the barrel and shell, a rotatable longitudinally movable shaft mounted axially of the barrel and shell and centrally thereof and carrying at one end a driving member which is fixed thereto and adapted to engage and drive a member of the engine to be started, means co-acting with the shell and shaft for actuating the shaft in its longitudinal movements, and means for rotating the barrel, said co-acting means comprising threads between the shell and shaft.

14. An engine starter drive including a rotatable barrel, a substantially cylindrical shell concentric of the barrel, a friction clutch operatively connecting the barrel and shell, a rotatable longitudinally movable shaft mounted axially of the barrel and shell and carrying at one end a driving member which is fixed thereto and adapted to engage and drive a member of the engine to be started, said shell and shaft being threaded to each other for the actuation of the shaft in its longitudinal movements, means for resisting rotary movement of such driving member and its shaft to assure longitudinal movement thereof for engagement with the engine member, and means for rotating the barrel.

15. An engine starter drive including a rotatable barrel, a substantially cylindrical shell concentric of the barrel, a friction clutch operatively connecting the barrel and shell, a rotatable longitudinally movable shaft mounted axially of the barrel and shell and carrying at one end a driving member adapted to engage and drive a member of the engine to be started, means coacting with the shell and shaft for actuating the shaft in its longitudinal movements, and means for rotating the barrel, said barrel being concentric with and surrounding the shell and shaft, the latter forming the central member thereof.

16. An engine starter drive including a rotatable barrel, a substantially cylindrical shell concentric of the barrel, a friction clutch operatively connecting the barrel and shell, a rotatable longitudinally movable shaft mounted axially of the barrel and shell and carrying at one end a driving member adapted to engage and drive a member of the engine to be started, means coacting with the shell and shaft for actuating the shaft in its longitudinal movements, and means for rotating the barrel, said barrel being provided with an interior annular rib on one side of which the clutch is located, and clutch tightening means located on the other side thereof and cooperating with the clutch, said clutch tightening means being enclosed by said barrel and carried by said shell.

17. An engine starter drive including a rotatable barrel, a substantially cylindrical shell concentric of the barrel, a friction clutch operatively connecting the barrel and shell, a rotatable longitudinally movable shaft mounted

- axially of the barrel and shell and carrying at one end a driving member adapted to engage and drive a member of the engine to be started, means coacting with the shell and shaft for actuating the shaft in its longitudinal movements, and means for rotating the barrel, said clutch comprising two sets of friction plates, one set being splined to the barrel and the other to the shell, and clutch 10 tightening means which are physically independent of said clutch plates. 18. An engine starter drive including a rotatable barrel, a substantially cylindrical shell concentric of the barrel, a friction clutch operatively connecting the barrel and shell, a rotatable longitudinally movable shaft mounted axially of the barrel and shell and carrying at one end a driving member adapted to engage and drive a member of the engine to be started, means coacting with the shell and shaft for actuating the shaft in its longitudinal movements, and means for rotating the barrel, said clutch comprising two sets of friction plates, one set being splined to the barrel and the other to the shell, and adjustable pressure applying means for the clutch including a series of coiled springs whose pressure is applied to the clutch plates, and a single adjustable device coacting with all of said springs 20 simultaneously for adjusting and predetermining the setting of the clutch. 19. An engine starter drive including a rotatable barrel, a substantially cylindrical shell concentric of the barrel, a friction clutch operatively connecting the barrel and shell, a rotatable longitudinally movable shaft mounted axially of the barrel and shell and carrying at one end a driving member adapted to engage and drive a member of the engine to be started, means coacting with the shell and shaft for actuating the shaft in its longitudinal movements, and means for rotating the barrel, said clutch comprising two sets of friction plates, one set being splined to the barrel and the other to the shell, and adjustable pressure applying means for the clutch including a series of coiled springs whose pressure is applied to the clutch plates, and a ring screw threaded on said shell and coacting with all 30 of said springs simultaneously for adjusting and predetermining the setting of the clutch. 20. An engine starter drive including a rotatable barrel, a substantially cylindrical shell arranged within and concentric of the barrel, a friction clutch operatively connecting the barrel and shell, a rotatable longitudinally movable driving member mounted axially and centrally of the barrel and shell and adapted to engage and drive a member of the engine to be started, means coacting with the shell and driving member for actuating the latter in its longitudinal movements, said barrel and shell being spaced apart to form an annular space accommodating the friction clutch. 21. An engine starter drive including a rotatable barrel, a substantially cylindrical shell arranged within and concentric of the barrel, a friction clutch operatively connecting the barrel and shell, a rotatable longitudinally movable driving member mounted axially and centrally of the barrel and shell and adapted to engage and drive a member of the engine to be started, means coacting with the shell and driving member for actuating the latter in its longitudinal movements, and tightening means for said clutch, said barrel and shell being spaced apart to form an annular space accommodating the clutch and its tightening means. 22. An engine starter drive including a rotatable barrel, a substantially cylindrical shell arranged within and concentric of the barrel, a friction clutch operatively connecting the barrel and shell, a rotatable longitudinally movable driving member mounted axially and centrally of the barrel and shell and adapted to engage and drive a member of the engine to be started, means coacting with the shell and driving member for actuating the latter in its longitudinal movements, and tightening means for said clutch, said barrel and shell being spaced apart to form an annular space accommodating the clutch and its tightening means, said clutch and tightening means being arranged in tandem relationship and occupying opposite ends of said annular space. 23. An engine starter drive including a rotatable barrel, a substantially cylindrical shell arranged within and concentric of the barrel, a friction clutch operatively connecting the barrel and shell, a rotatable longitudinally movable driving member mounted axially and centrally of the barrel and shell and adapted to engage and drive a member of the engine to be started, means coacting with the shell and driving member for actuating the latter in its longitudinal movements, said shell being rotatable but immovable longitudinally. 24. An engine starter drive including a rotatable barrel, a substantially cylindrical shell arranged within and concentric of the barrel, a friction clutch operatively connecting the barrel and shell, a rotatable longitudinally movable driving member mounted axially and centrally of the barrel and shell and adapted to engage and drive a member of the engine to be started, means coacting with the shell and driving member for actuating the latter in its longitudinal movements, said shell being rotatable but immovable longitudinally, and said barrel and shell being spaced apart to form an annular space accommodating the friction clutch which is composed of two sets of friction plates splined respectively to the barrel and shell. 25. An engine starter drive including a rotatable barrel, a substantially cylindrical ro- 100 105 110 115 120 125 130

tatable shell concentrically within said barrel leaving an annular space between them, a friction clutch in said space constantly making connection of limited torque-transmitting capacity between said barrel and shell, a driving member mounted within and coaxially of said shell and arranged for longitudinal movement to engage and rotation to crank a member of an engine to be started, 10 and operative connections between said shell and driving member for rotating the latter in its engine-cranking position.

26. An engine starter drive including a rotatable barrel, a substantially cylindrical shell 15 concentrically within said barrel leaving an annular space between them, said shell being rotatable but substantially immovable longitudinally with respect to said barrel, a multiple-disk friction clutch in said space constantly 20 making connection of limited torque-transmitting capacity between said barrel and shell, a driving member mounted within and coaxially of said shell and arranged for longitudinal movement to engage and rotation to 25 crank a member of an engine to be started, and operative connections between said shell and driving member for rotating the latter in its engine-cranking position.

27. An engine starter drive including a 30 rotatable barrel having an open end, a substantially cylindrical shell concentrically within said barrel leaving an annular space between them, said shell being rotatable but substantially immovable longitudinally with 35 respect to said barrel, a multiple-disk friction clutch in said annular space constantly making connection of limited torque-transmitting capacity between said barrel and shell, adjustable clutch-tightening means arranged 40 in said space in tandem with said clutch and accessible for adjustment at the open end of the barrel, a driving member mounted within and coaxially of said shell and arranged for longitudinal movement to 45 engage and rotation to crank a member of an engine to be started, and operative connections between said shell and driving member for rotating the latter in its engine-cranking position.
